UNITED STATES PATENT OFFICE.

ROBERT WILLIAMSON, OF MALPAS, ENGLAND, AND WILLIAM GWYNNE THOMAS, OF CARDIFF, WALES.

APPARATUS FOR ANGULAR BENDING OR CURVING OF METAL SHEETS AND BARS.

Application filed July 25, 1925, Serial No. 46,084, and in Great Britain August 7, 1924.

This invention relates to apparatus for the angular bending or curving of metal sheets and bars, and has for its object a construction which enables any desired bending or curving to be effected without any addition to or changing of the parts of the apparatus.

We attain this end by the construction shown in the accompanying drawings in which Figure 1 is a view in side elevation, Figure 2 is a view in end elevation, Figure 3 is a view in plan, and Figures 4 and 5 are views partly in section illustrating the use of the device and showing different forms of fullers which may be employed.

Throughout the views similar parts are marked with like numerals of reference.

On a bed plate 1 adapted to be mounted in a hydraulic press are mounted two rollers 2 and 2 in each of which is a shaped longitudinally arranged depression 3 which converts said rollers into cams. The cam rollers are coupled together by suitable gearing so that they can be caused to rotate simultaneously in opposite directions and means is provided to lock said rollers against rotation. We prefer to use worm gearing as shown in the accompanying drawings as such provides an automatic lock. In such a construction each cam roller carries a worm wheel 4 with which two opposed worms 5 carried by a common shaft 6 engages, said shaft being provided with means such as the squared ends 7 by which it can be rotated. In the bed plate 1 midway between the cam rollers 2 and 2 are pivoted two former plates 9 and 9 the free edges of which engage the cam rollers 2.

A convenient method of mounting the cam rollers 2 is to form transverse grooves in the bed plate 1 of a suitable shape to form bearings for said rollers, and a convenient method of pivoting the former plates to said bed plate is to form a centrally arranged semi-circular recess 8 in it and to provide semi-circular projections 10 on the former plates to fit in said recess 8 said projections 10 being slotted so that they interengage like the plates of a hinge. Side plates 13 are mounted on the bed plate to prevent lateral displacement of the former plates and the cam rollers.

In operation the bar to be treated, shown in full lines as an angle bar in Figures 4 and 5, is placed between the two former

plates 9, which have been previously set to the required angle, and a fuller 14, which is adapted to be carried by the ram of a hydraulic press, is caused to engage the bar and press or force out its two sides until they come into contact with the faces of the former plates as shown in dot and dash lines in said Figures 4 and 5.

The operative part of the fuller 14 may either take the form of a roller 15 as shown in Figure 4 or of a bar-shaped projection 16 as shown in Figure 5. If the former a semi-circular depression 17 is formed in the body part of the fuller for the roller 15 to engage with said roller being connected to said body part by links 18 which will allow the necessary relative movement between the roller and the body part to ensure contact between said parts when the tool is in action.

What we claim is:

1. An apparatus for bending or curving metal sheets and bars comprising a bed plate, two cams mounted in parallel relation to one another on said bed plate, means for rotating said cams said means comprising means for fixing said cams after and against rotation, and a pair of formers hinged to the bed plate between said cams and adapted to contact with them.

2. An apparatus for bending or curving metal sheets and bars comprising a bed plate, two cam rollers mounted in parallel relation to one another on said bed plate, means for rotating said cam rollers in opposite directions, said means comprising means for fixing said cam rollers after and against rotation, and a pair of former plates hinged to the bed plate between said cam rollers and adapted to engage them.

3. An apparatus for bending and curving metal sheets and bars consisting of a bed plate, two cams mounted on said bed plate in suitable bearings in parallel relation to one another, worm gearing coupling said cams to one another in such a manner that they have simultaneous movement in opposite directions, means whereby motion may be imparted to said gearing, and a pair of former plates hinged to the bed plate and adapted to engage said cams.

4. An apparatus for bending and curving metal sheets and bars consisting of a bed plate, two cam rollers mounted on said bed plate in suitable bearings in parallel relation to one another, worm gearing coupling said

- rollers to one another in such a manner that they have simultaneous movement in opposite directions, means whereby motion may be imparted to said gearing, a pair of former plates hinged to the bed plate between said cam rollers and adapted to contact with said rollers and a fuller adapted to be mounted on the ram of a hydraulic press and to coat with said former plates.
10. 5. An apparatus for bending and curving metal sheets and bars consisting of a bed plate, two cam rollers mounted in parallel relation to one another in grooves in the bed plate, gearing coupling said cam rollers to one another so that they have simultaneous movement in opposite directions, means for imparting motion to said gearing, said gearing including means for fixing said cam rollers against rotation, a pair of former plates hinged to the bed plate midway between the cam rollers and adapted to engage said cam rollers and a fuller adapted to coat with the former plates comprising a body part, a roller and a pair of links coupling said roller to said body part in such a manner as will allow the roller and the body part to come into contact.
6. An apparatus for bending and curving metal sheets and bars consisting of a bed plate, two cam rollers mounted in parallel relation to one another in grooves in the base plate, worm gearing coupling said cam rollers to one another so that they have simultaneous movement in opposite directions, means for imparting motion to said gearing, a pair of former plates hinged to the bed plate midway between the cam rollers and adapted to engage said cam rollers and a fuller adapted to coat with said former plates comprising a body part, a roller, and a pair of links coupling said roller to said body part in such a manner that said roller can contact with said body part.
7. An apparatus for bending or curving metal sheets and bars comprising a bed plate having three transverse semi-circular recesses in its upper face, a cam roller mounted in each of the outer recesses, a pair of former plates having interengaging semi-circular projections by which they are mounted in the central recess in the bed plate, side plates secured to the bed plate to prevent lateral movement of the cam rollers and the former plates, gearing for coupling the cam rollers together, said gearing including means for locking said cam rollers against movement after they have been rotatably adjusted, and means for imparting motion to said gearing.
8. An apparatus for bending or curving metal sheets and bars comprising a bed plate adapted to be mounted in a hydraulic press having three transverse semi-circular recesses in its upper face, a cam roller mounted in each of the outer recesses, a pair of former plates having interengaging semi-circular projections by which they are mounted in the central recess in the bed plate, side plates secured to the bed plate to prevent lateral movement of the cam rollers and the former plates, gearing for coupling the cam rollers together, said gearing including means for locking said cam rollers against movement after they have been rotatably adjusted, means for imparting motion to said gearing and a fuller adapted to be carried by the ram of a hydraulic press and to coat with said former plates, said fuller comprising a body part adapted to be mounted in said ram and having a semi-circular groove, a roller, and a pair of links coupling said roller to said body part which will allow said roller to come into contact with the semi-circular groove in said body part.

ROBT. WILLIAMSON.
WILLIAM GWYNNE THOMAS.
